UNITED STATES PATENT OFFICE.

NICOLA PEDULLA, OF MACDONALDTON, PENNSYLVANIA.

HAND MINING-MACHINE.

1,184,205.

Specification of Letters Patent. Patented May 23, 1916.

Application filed September 24, 1915. Serial No. 52,388.

To all whom it may concern:

Be it known that I, NICOLA PEDULLA, a citizen of the United States, residing at Macdonaldton, in the county of Somerset and State of Pennsylvania, have invented certain new and useful Improvements in Hand Mining-Machines, of which the following is a full, clear, and exact specification.

10 This invention relates to mining machines and especially to coal cutting machines adapted to be operated by hand.

One object of the invention is to provide a machine of this kind which is simple in 15 construction, inexpensive to manufacture, and which may be easily operated by unskilled workmen.

Another object is to provide the machine with improved means for holding it in different positions for cutting at different 20 levels.

A further object of the invention is to construct the machine in such a way that most of its operating parts are interchangeable and may be quickly assembled and 25 taken apart as occasion may require.

Other objects will appear as the description proceeds.

The invention will be first hereinafter described in connection with the accompanying drawings, and then more specifically defined in the claims at the end of the description.

In the accompanying drawings, wherein 35 similar reference characters are used to designate the corresponding parts throughout the several views: Figure 1 is a broken plan view of a machine constructed substantially in accordance with the present invention. Fig. 2 is a longitudinal vertical section taken centrally through the machine. Fig. 3 is an enlarged detailed section through the spacing sleeves and splined beveled pinion on one of the bit-carrying 40 shafts, said shaft being also shown in engagement with one of the internally screw-threaded passages in one of the removable cross bars. Fig. 4 is a detailed section on the line IV—IV of Fig. 1, showing the 45 wedge at the end of the removable cross bar through which the shafts are passed, and the removable block for retaining the wedge and cross bar in place. Fig. 5 is a side elevation of the coal cutting machine as it appears in operation for cutting at the floor 50 level, and Fig. 6 is a similar view showing

how the machine is supported for cutting above the floor level.

The operating parts of the machine are mounted upon a rectangular frame comprising side members 1 connected by bottom cross pieces 2 and upper cross pieces 3. Pockets 4 are formed in the inner faces of the side pieces 1 to receive and support cross bars 5 having internally screw-threaded 60 passages 6 to be operatively engaged by threaded shafts 7. There are preferably two of these cross bars 5, one being arranged near each end of the frame. Each cross bar 5 is made in two sections, the division being 65 made horizontally and midway through the screw-threaded passages 6 to permit quick adjustment and removal of the shafts 7 from said passages. The two sections 5^a and 5^b, Fig. 4, are held together by screws 70 8, one of which is preferably placed between each pair of adjacent passages 6.

To hold the cross bars 5 firmly in position and prevent rattling, wedges 9 are placed at the ends of these bars in the pockets 4. The 80 forward one of the bars 5 is held in place in its pockets 4 by blocks 10 secured by screws 11 to the upper edges of the side pieces 1 of the frame. These blocks also serve to hold the wedges 9 at the ends of the forward cross bar in place, as best shown in Fig. 4. The other cross bar is retained in its pockets by a platform 12 which extends across the frame and preferably fits between the rear upper cross piece of the frame and 90 the blocks 10. This platform is removably held in place by screws 13 and serves to retain the wedges 9 at the ends of the rear cross bar in place in the same manner as the blocks 10 retain the wedges at the ends of 95 the forward cross bar. The lateral edges of the platform 12 are preferably provided with overhanging flanges 14 which fit down over the outer edges of the side pieces 1 of the frame and rest upon longitudinal ledges 100 15 rigidly attached to or formed integral with said side pieces.

Any suitable number of shafts 7 may be employed, but seven is the preferred number, as shown in Fig. 1. Each of these 105 shafts engages screw-threaded passages 6 in the cross bars 5 and is provided with a longitudinal groove 16 by means of which a beveled pinion 17 is splined thereto. The beveled pinion 17 is positioned between the 110 two cross bars 5 by a pair of sleeves or spacing collars 18, one of which is arranged

at each side of the pinions. The relative lengths of the sleeves 18 vary on the different shafts, so that the pinions 17 on the seven shafts are arranged in an arc in a 5 horizontal plane.

The platform 12 has seven short vertical shafts 19 journaled therein and arranged in spaced relation and in an arc to correspond with the positions of the pinions 17 10 on the shafts 7. Each of the shafts 19 carries a beveled pinion 20 on its lower end below the platform 12 to mesh with the pinions 17 on the corresponding one of the shafts 7. A gear 21 is carried by the upper 15 end of each of the shafts 19 on the upper face of the platform 12, and all seven of these gears 21 mesh with a large gear wheel 22 journaled on the platform 12 and provided with a handle 23 for turning the 20 same. The gear wheel 22 is preferably made with a skeleton central portion but a heavy rim, so that it will act like a fly wheel, its momentum helping to carry it around in operation.

25 Each of the shafts 7 carries a bit 24 on its forward end. These bits have plug and socket connections with the shafts and are retained on the shafts by set screws 25. The cutting end 26 of each bit is of greater diameter than its shank, and alternate ones of the shafts are arranged slightly in advance of the others so that said flared cutting ends 26 of the bits will overlap one another, as clearly illustrated in Fig. 1. It will be understood, of course, that the spacing of the shafts 7 apart is determined so as to provide for this overlapping of the flared cutting ends of the bits. The shafts 7 are headed on their rear ends, as at 27 to form stops 30 against the rear one of the cross bars 5 for limiting the advance of said shafts. It will be noted that the heads 27 on alternate ones only of the shafts will come in contact with the rear cross bar 5, but this will be sufficient 35 to stop the advance of all the shafts. Of course, alternate ones of the shafts 7 may be made a trifle shorter than the others so that their heads will also contact with the rear cross bar, but it is considered preferable to make all of the shafts the same length so 40 that they will be interchangeable.

To provide for rigidly holding the frame of the machine stationary during the advance of the shafts 7, there are perforated 45 lugs 28 swiveled to the side pieces 1, and stakes 29, Fig. 5, are passed through the perforations in said lugs and driven into the floor of the mine chamber. The lugs 28 are fitted with set screws 30 for binding the 50 stakes in the perforations so as to prevent vertical as well as lateral and longitudinal movement of the machine while in operation. Instead of the stakes 29, long rods 31 may be 55 passed through the perforations in the lugs 28 and extend from the floor to the ceiling 60

of the mine chamber, thereby allowing for the machine to be moved upward for cutting at a higher level, as shown in Fig. 6. The set screws 30 are used for clamping the rods 31 to support the machine at any desired 70 level.

The operation of the machine is very simple and is probably understood already from the foregoing description. The large gear wheel 22 is turned by means of the handle 23 75 and rotates the meshing gears 21. The rotary movement of these gears 21 is communicated through the short shafts 19 to the beveled pinions 20 and by them to the beveled pinions 17 splined on the shafts 7. In this 80 way, all of the shafts 7 are turned in unison and owing to their threaded engagement with the passages 6 in the cross bars 5, they will be either advanced or retracted according to the direction of rotation of the gear wheel 85 22. When advanced, the bits 24 on the forward ends of the shafts 7 will cut into the wall of coal, as illustrated in Figs. 5 and 6. The overlapping of the flared cutting ends 90 26 of the bits 24 will produce a continuous slot or groove in the coal instead of a series of detached round holes as would be the case if the cutting ends of the bits were spaced apart instead of overlapped. When slots or 95 grooves have been cut at the desired levels with the machine in one position, the stakes 29 or anchoring rods 31 are removed from the lugs 28 and the machine moved to one side by grasping the handles 32 shown in Figs. 5 and 6. Only two men are required to 100 operate and move the machine. In operation, one man turns the large gear wheel 22 for actuating the bits, while the other man removes the coal dust from the slot or groove being cut so as to leave a clear passage for 105 the entrance of the bits.

Having thus described my invention, what I claim as new and desire to secure by Letters Patent of the United States is:

1. In a mining machine, the combination 110 with a frame having a top plate and horizontally extending screw-threaded passages below said plate, of screw-threaded shafts fitted in said passages, bits carried by said shafts, pinions splined on the shafts, vertical auxiliary shafts equal in number to the screw-threaded shafts and journaled in the top plate, pinions carried by the lower ends of the auxiliary shafts and meshing respectively with the pinions splined on the 120 threaded shafts, gears on the upper ends of the auxiliary shafts above the top plate, and a horizontal gear wheel disposed above the top plate and meshing with all of said gears for simultaneously actuating all of the bits. 125

2. In a mining machine, the combination with a frame having a top plate and horizontally extending screw-threaded passages, bits carried by said shafts, means for spacing said pinions on the shafts whereby they 130

are arranged in an arcuate line across the frame, auxiliary shafts equal in number to the screw-threaded shafts, said auxiliary shafts being journaled in the top plate and 5 also arranged in an arcuate line, pinions carried by the lower ends of the auxiliary shafts and meshing respectively with the pinions splined on the threaded shafts, gears on the

upper ends of the auxiliary shafts above the top plate and a horizontal gear wheel disposed above the top plate and meshing with all of said gears for simultaneously actuating all of the bits. 10

In testimony whereof I have signed my name to this specification.

NICOLA PEDULLA.
